UNITED STATES PATENT OFFICE.

MORETON F. PURVEY, OF DETROIT, MICHIGAN, ASSIGNOR TO THE PUR-VEY CARBURETOR CORPORATION, A CORPORATION OF DELAWARE.

CARBURETOR.

Application filed July 17, 1922. Serial No. 575,506.

This invention relates to carburetors and the object of the invention is to provide a carburetor of simple construction and efficient operation in which the liquid fuel is fed into the air conduit in a fine mist or fog. The principal object of the invention is to provide a carburetor having two fuel inlets extending into the air conduit, the said inlets being each provided at the discharge ends with a chamber containing a ball about which the fuel must pass and which is rapidly vibrated by the fuel passing thereabout. A further object of the invention is to provide a carburetor of the character described comprising a pair of fuel inlets each provided with a ball in the end thereof over which the fuel is spread in a thin film while being drawn from the fuel inlets, the liquid fuel being discharged from the fuel inlets into the air conduit in a fine mist or fog. A further object of the invention is to provide a carburetor of the character described comprising a throttle valve adapted when closed to prevent flow of fuel from one of the fuel inlets and also prevent flow of air through the air conduit at the same time allowing flow of fuel from the other fuel conduit, the said valve when opened allowing flow of air through the air conduit and flow of fuel from both fuel inlets. These objects and the several novel features of the invention are hereinafter more fully described and claimed and the preferred form of construction by which these objects are attained is shown in the accompanying drawings in which—

Fig. 1 is a plan view of a carburetor embodying my invention.

Fig. 2 is a side elevation thereof.

Fig. 3 is a section taken on line 3—3 of Fig. 1.

Fig. 4 is a section taken on line 4—4 of Fig. 3.

Fig. 5 is a section taken on line 5—5 of Fig. 1.

Fig. 6 is a section through the air conduit of the carburetor.

Fig. 7 is a detail of a section through one of the nozzles.

As shown in Figs. 1 and 5, a bowl 1 is preferably provided and a connection 2 for a liquid fuel line is threaded onto a boss 3 on the bottom of the bowl. A needle valve 4 is provided for closing the fuel inlet 5 and a pivoted arm 6 is provided for operat-

ing the needle valve 4, the arm being secured to a float 7 within the bowl. The bowl is provided with a pair of enlargements 8 and 9 on one side as shown in Figs. 2 and 3 which are provided with vertical channels 10 in communication with the bowl by means of the channels 11 opening thereinto. Opening into each channel 10 is an air inlet channel 12 having an air tube 13 in communication therewith and through which the air may pass. The channels 10 at the upper end are restricted and provided with small apertures 14 therethrough and a member 15 is threaded into the upper end of the enlargement 8 and a member 16 is threaded into the upper end of the enlargement 9. Both of these members 15 and 16 are provided with apertures 17 in communication with the apertures 14 of the members 8 and 9 and at the upper end each member 15 and 16 is provided with a chamber or recess 18. Within each chamber 18 is a ball 19 normally closing the aperture 17 and a pin 20 is provided through the upper end of each member 15 and 16 which prevents the ball 19 from being drawn out of the recess or chamber 18 by the suction of the engine. The air conduit 21 is slipped over the members 15 and 16 and is bolted to a lug 22 on the bowl by means of a bolt 23 passing through the lug 24 as shown in Fig. 3. This air conduit 21 is provided, as shown in Figs. 1 and 2, with an air inlet 25 having a butterfly valve 26 therein which is operable by a bell crank 27 to regulate the flow of air, the valve 26 being provided with a spring 28 normally holding the valve in the open position. This air conduit 21 is provided with a baffle 36 between the air inlet end 25 and the throttle valve so that the air is directed through the oblong opening 37 before passing about the fuel inlets. By passing the air through the restricted opening 37 a vacuum is produced about the fuel inlets which aids in drawing the fuel into the intake manifold as will be readily understood. As shown more particularly in Fig. 3 the throttle valve 29 in the air conduit is provided with an aperture 31 which registers over the chamber 18 of the member 16 when closed. By this means when the throttle valve is closed the air conduit is closed with the exception of the aperture 31 and the liquid fuel is not drawn through the member 15, the entire supply of liquid fuel and

air flowing through the member 16 and providing a rich mixture for starting the engine and for idling.

In operation the liquid fuel flows into the bowl 1 until the cork float 7 is in the position shown in full lines in Fig. 5. At this time the level of the gasoline is at about the line A—A shown in Fig. 3 and partially fills the horizontal apertures 12. When the engine is started the throttle valve 29 is closed as shown and the entire vacuum produced by the engine is relieved through the aperture 31 of the said throttle valve. This vacuum draws air through the tube 13 and through the aperture 12 where the air is mixed with the gasoline and passes upwardly through the small aperture 14 through the aperture 17 of the member 16 and through the chamber 18 about the ball 19 and into the air conduit through the aperture 31 of the throttle valve. The liquid fuel in passing upwardly through the aperture 17 is spread over the ball 19 and on account of the vacuum the ball 19 is practically maintained between the pin 20 and its seat and the mixture of fuel and air passes through the aperture 31 in a fine mist or fog. This provides a rich mixture for starting the engine and for idling speeds and when the throttle valve 29 is opened, as shown in dotted lines in Fig. 3 and full lines in Fig. 1, the air flows through the air inlet 25 and in passing over the upper end of the members 15 and 16 air is drawn through the tubes 13, apertures 12, the small apertures 14, through the apertures 17 and about the balls 19 into the air conduit, the air being mixed with the liquid fuel in the channel 12 and by vibration of the balls 19 the mixed air and fuel passes into the air conduit as a mist or fog where it is further mixed with air. When the throttle valve 29 is open as shown in Fig. 6 the mixed air and fuel is drawn through both members 15 and 16 which causes both balls 19 to vibrate very rapidly so that the liquid fuel is broken up into fine particles and is drawn into the air conduit in a fine vaporized state. As shown in Fig. 2 a pair of adjusting screws 32 are provided which are adjustable to restrict or regulate the small apertures 14 through which the fuel and air passes to the members 15 and 16, the screws 33, 34 and 35 being used merely to plug the ends of the different apertures and prevent leakage of fuel. It will thus be seen that the closing

of the throttle valve 29 allows a sufficient flow of gasoline for idling speeds and opening of the throttle valve provides a leaner mixture for a higher range of speed. It will also be noted that this carburetor is very safe and practically fireproof in use. For instance, should the timing of the engine be disarranged and a backfire occur in the air conduit 21, the pressure will cause the balls 19 to seat tightly and close the fuel feed apertures 17 thus preventing the fire from coming in contact with the liquid fuel which often results disastrously.

From the foregoing description it becomes evident that the device is very simple and efficient in operation, may be easily and cheaply manufactured, is formed of few parts which will not easily get out of order and provides a device which accomplishes the objects described.

Having thus fully described my invention, its utility and mode of operation, what I claim and desire to secure by Letters Patent of the United States is—

In a carburetor, a main air conduit, a pair of fuel feed lines extending into the conduit and terminating at different heights therein, the fuel conduit of greatest height having a recessed end portion terminating in a plane at a right angle to the axis of the conduit, a ball in the recess of less diameter than the said recess and normally closing said conduit, a throttle valve in the air conduit adapted when open to subject both fuel feed lines to influence of air passing therethrough, said throttle valve being adapted to be turned to closed position to lie in contact with the end of the fuel conduit of greatest height, said valve having an opening of less diameter than the said recess at the conduit end and providing when the valve is closed a discharge opening for the said highest fuel feed conduit into the main air conduit above the valve, the throttle valve otherwise practically closing the conduit to flow of air therethrough, each fuel feed conduit being connected with a source of fuel supply and each having a second conduit connected therewith opening to atmosphere, and an air inlet conduit for the said main air conduit provided with a restricted opening thereinto.

In testimony whereof, I sign this specification.

MORETON F. PURVEY.
